UNITED STATES PATENT OFFICE.

EBEN T. BRADBURY, OF ST. LOUIS, MISSOURI.

MACHINE FOR MANUFACTURING TRUNK SLATS, STRIPS, AND MOLDINGS.

1,217,907.

Specification of Letters Patent. Patented Mar. 6, 1917.

Application filed January 24, 1914. Serial No. 814,210.

To all whom it may concern:

Be it known that I, EBEN T. BRADBURY, a citizen of the United States, residing at St. Louis, Missouri, have invented certain new and useful Improvements in Machines for Manufacturing Trunk Slats, Strips, and Moldings, of which the following is a specification.

My present invention relates to improvements in machines for manufacturing wooden slats or strips of the character used for strengthening or reinforcing trunks and similar articles, and other strips and moldings.

Among the objects of the invention are to produce a simple, economical, durable and efficient machine which will produce at a single operation a plurality of properly dressed slats, which may be operated at high speed so as to have a large output, and which will deliver the slats in assembled condition convenient for bundling.

With these and possibly other objects in view, the invention includes the novel features of construction and arrangement and combination of parts hereinafter described and particularly defined by the appended claims.

A machine embodying my invention is illustrated in the accompanying drawings, in which—

Figure 1 is a side elevation;

Fig. 2 is a plan view;

Fig. 3 is a sectional detail;

Figs. 4 and 4^a are detail views of forms of knife;

Figs. 5 and 6 are detail views of the stacking means; and

Fig. 7 is a detail view of the spring presser finger.

Referring by reference characters to this drawing, the numeral 1 designates the frame of the machine having a bed or table 2 to receive the blanks to be operated upon.

These blanks are simply plain unfinished strips of wood of approximately the shape of a lath and in order to enable a plurality of them to be passed simultaneously and in proper position through the machine, the bed or table is provided with a plurality of longitudinally disposed ribs 3 forming between them channels or guideways within which the strips travel between the feed rolls and past the cutters.

Two pairs of feed rolls are used, one pair,

4, 4^a, being located in advance of the cutters and the other pair 5, 5^a, in rear thereof, each pair comprising an upper and a lower roll between which the blanks are gripped and by which they are fed forward. The peripheries of the lower rolls project through openings in the bed, and the rolls are driven by gearing in the customary manner. These rolls are of the sectional yielding type, that is the roll shaft carries a plurality of spring or elastically supported corrugated gripping rings which, while all turning in unison with the roll shaft, yet can yield individually sufficiently to compensate for irregularities in the stock, but as the specific construction of the roll itself forms no part of my invention detailed description thereof is unnecessary herein.

To produce the properly finished slat the blank must be dressed on its upper surface and have its sides rounded and dressed and for this purpose I provide cutting edges of a special shape for each guideway, as shown in detail in Figs. 4 and 4^a.

In Fig. 4 I show a construction in which one set of straight edge knives are used to dress the upper faces of the blanks as indicated at 6, and a separate set of cutters 6^a for trimming or dressing the side edges of the blanks.

If the cutter head be one having four faces, two of these faces may be provided with cutters 6, and these cutters may extend the entire length of the cutter head, being secured thereto by bolts 6^x or in any desired manner.

The other two faces are provided with pairs of reversely placed knives secured by bolts 6^b having their heads adjustably seated in the longitudinal dovetailed grooves 7^a of the cutter head 7, the projecting portions of these knives having curved cutting edges 6^c for trimming the side edges of the blanks, as clearly shown in Fig. 4.

By means of the slot 7^a the knives or cutters 6^a may be adjusted toward or from each other to suit different sizes of blanks or strips.

Instead of having the straight edges on one set of cutters and the curved edges on another, I may combine them as shown in Fig. 4^a. In this form each cutter 6^a would dress the top and sides of the strip, and adjustment would be effected by removing the cutters and replacing them with ones of dif-

ferent width. Slots or grooves 2^a are provided in the bed into which the projecting portions 6^c of the blades can pass, thus enabling them to cut clear past the bottom 5 edges of the blanks.

The cutter head 7 is journaled in the frame of the machine and driven in any desired manner from any suitable source of power.

10 In advance of the cutter head and between it and the front feed roll is located a chip breaker 8, and in rear of the cutter a presser bar 9. Owing to the projections on the knives above referred to this presser bar can 15 not be set very close to the edges 6^a of the cutters. Some woods, when cut to the thinness necessary for trunk staves, have a tendency to curl on passing the cutter, and to prevent any danger of the strip catching on 20 the edge of the presser bar the lower edge of the bar is provided with a plurality of forwardly and slightly upwardly extending fingers 9^a which project in between the portions 6^a of the rotating knives.

25 At the rear end of the machine I provide means for stacking the finished staves which comprises a receiving box 10 having partitions 10^a forming intervening compartments which are in alinement with the guideways 30 of the bed of the machine. This collecting box has a bottom 11 inclining downwardly from the delivery end of the table or bed, and as the finished strips are fed from the machine their advancing ends pass between 35 the partitions 10^a, and as soon as their opposite ends have cleared the hold down bar 12 which is adjustable toward and from the end of the bed, the strips or stays tip downward and slide into place either on the inclined 40 bottoms of the compartments, or onto the strips previously deposited therein, from which they may be taken in bundles ready for packing.

In order that the machine may be adapted 45 to handle different widths of strips, I provide in one wall of each guideway a yielding presser device for pressing the strip against the opposite wall of the guideway. This I preferably accomplish by forming a 50 recess 13 in each guideway within which is located a spring presser arm or finger 14. One end of this finger is of ring form, as indicated at 14^a, provided with recesses α in its upper edge to receive the projections α' 55 of a cap or clamping ring 15 secured to the bed by a bolt 16.

By this means the spring fingers may be adjusted to project more or less from their recesses to act against the sides of the blanks 60 and thus hold them in alinement with the knives.

It will be understood that with narrower

blanks, knives of correspondingly reduced width would be used.

It will be understood that while I have described my invention as designed more especially for the manufacture of trunk slats, it is not confined to the production of this specific article, and is capable of being used in the production of moldings or strips of other forms.

In order that the receiving box or hopper may be adapted for strips of varying length, its end gate 11^a is made adjustable.

This may be conveniently accomplished 75 by simply sliding it into the desired pairs of grooves 10^b.

As the bottom is moved upwardly, corresponding reduction is necessary in the width of the partitions, and this may be effected by 80 making the partitions sectional, as indicated at α , and having their lower ends provided with a pin and slot or other interlocking connection with the bottom as indicated at α' and their tops suitably held by members 85 or bars b .

Having thus described my invention what I claim is:

1. In a machine of the class described, a bed having a plurality of longitudinally disposed ribs extending throughout its length and forming channels or guide ways within which the blanks are adapted to travel, a rotary cutter head having cutters corresponding to each guideway and shaped to dress the 90 top and sides of the blanks, feed rollers for moving the blanks across the bed, a transversely disposed chip breaker located in advance of said cutter head and a corresponding presser bar located in rear of said cutter 100 head provided at its forward end with integral fingers projecting slightly upward between the several cutters, substantially as described.

2. In a machine of the class described, a 105 bed having a plurality of longitudinally disposed ribs extending throughout its length forming channels or guideways within which the blanks are adapted to travel, rotary cutter means provided with cutters corresponding to each guide-way, feeding means for the blanks, a chip breaker located in advance of the cutter means, a presser bar located in rear of the cutter means, a hopper having a bottom inclining downwardly from 110 the delivery end of the bed and provided with partitions forming compartments alining with the said channels or guide-ways and a hold-down bar over the guide-ways, substantially as described.

EBEN T. BRADBURY.
